CIGAR TUBE

Maitlon T. Russell, Jr., Philadelphia, Pa., and Robert A. Serafini, North Tonawanda, N.Y., assignors to Bayuk Cigars Incorporated, Philadelphia, Pa.

Filed Jan. 15, 1973, Ser. No. 323,880

Term of patent 14 years

Int. Cl. D9—05

U.S. Cl. D27—50

FIG. 1 is a front elevational view of a cigar tube showing our new design;

FIG. 2 is a left side elevational view;

FIG. 3 is a right side elevational view;

FIG. 4 is a rear elevational view;

FIG. 5 is a top plan view; and

FIG. 6 is a bottom plan view.

It is understood that the surface ornamentation partially shown on the tube portion in FIGS. 1-3 is continuous along the surfaces in the manner shown in FIG. 4.

We claim:

The ornamental design for a cigar tube, as shown and described.
